APPARATUS FOR PROJECTING ROUNDS
OF AMMUNITION

Lewis Motley, Much Wenlock, England

Application May 4, 1948, Serial No. 24,955
In Great Britain February 3, 1947

10 Claims. (Cl. 89—33)

1

This invention relates to apparatus for discharging rounds of ammunition. The invention refers particularly to launching apparatus for projectiles of the self-propelled or rocket type, but it is also applicable to other types of ordnance, bomb throwers and the like.

The object of the invention is the provision of improvements in such apparatus and the invention consists broadly of an apparatus comprising two containers for the rounds, a breech element adapted to reciprocate to and from two positions, and means whereby, as said breech element reciprocates, it alternately conveys rounds from each container to a common location to enable said rounds to be discharged.

In order that the invention may be the more clearly understood an apparatus in accordance therewith, for discharging projectiles of the rocket type, will now be described, reference being made to the accompanying drawings, wherein:

Figure 1 is a broken away perspective view of the general arrangement.

Figure 2 is a cross section of the lower part of the apparatus illustrating the power means for reciprocating the breech block and the means for controlling the feeding of the rounds thereto, the section being in part on line II—II of Figure 3.

Figure 3 is a section on line III—III of Figure 2.

Figure 4 is a plan of the mechanism for timing the reciprocation of the breech block.

Figure 5 is a section on line V—V of Figure 4.

Figure 6 is a section on line VI—VI of Figure 4.

Figure 7a is a section on line VII—VII of Figure 4.

Figure 7b is a similar view to Figure 7a but with the parts in a different position.

Figure 8 is a section on line VIII—VIII of Figure 4.

Figure 9 is a face view of a cam part included in Figures 4, 5, 7a and 7b.

Figure 10 is a view illustrating the co-operation of the cam part illustrated in Figure 9 with the catches which it controls.

Figure 11 is a perspective view illustrating a switch-controlling device which operates in response to the firing of the rounds.

Figure 12 is a sectional view of the same showing also the switch controlled thereby.

Figure 13 is a plan of a detail.

Referring to the drawings the apparatus comprises two parallel feed chutes 1 and 2 each of which is adapted to contain a column of the rounds 3 with their axes transverse to the di-

rection of feed along the chutes and parallel to the launching tube 4. The rounds 3 are biased by means of pushers 5 pressing on the uppermost round of each column to the outlet ends of the chutes at the bottom thereof, and the said outlet ends lead to a reciprocating breech element 6 located just behind the rear end of the launching tube 4. This breech element 6 covers and closes the bottom or outlet ends of the two chutes, but said breech element has, in its upper surface, two grooves or channels 7 and 8 which appertain respectively to the two chutes 1 and 2. The reciprocating of said breech element is horizontal from side to side, and the arrangement is such that when said breech element is at one end of its stroke (the left hand end according to Figure 1), the channel 7 is immediately in registration with the bottom end of the chute 1, while the channel 8 is directly in line with the launching tube 4, and, when said breech element is at the other end of its stroke, the channel 8 is immediately in registration with the bottom of the chute 2, while the channel 7 is directly in line with said launching tube. When either channel 7 or 8 is in registration with the bottom end of its respective chute 1 or 2, the whole column of rounds 3 in said chute is enabled to move down under its bias until the leading round is within said channel, and when either channel is in line with the launching tube, the round therein is immediately behind and coaxial with said launching tube, and in position to be fired.

It will of course be appreciated that the channels 7 and 8 must be open both at their front and rear ends and that the projectile at the firing position must have its rear end exposed to the atmosphere and its front end with free access to the launching tube. Thus the projectile can be fired by a firing mechanism behind it and the rear blast can pass freely to the atmosphere. Each of the channels is formed with longitudinal ribs 9 which actually support the projectiles so that there is considerable clearance between the external periphery of the projectile and the internal periphery of the major portion of the channel.

The breech element moves in a rectangular chamber having a roof 10, two side walls 11, a bottom 12, a rear wall 13 and a front wall 14. The two chutes 1 and 2 extend up from the roof 10 of this chamber as shown and the launching tube 4 extends from the front wall 14 of said chamber. The rear wall 13 of said chamber has an opening in it in line with the round in the firing position, and, sealed in this opening is an

outlet tube 15 through which the exhaust gases from the round escape rearwardly. The roof 10 of said chamber serves, together with the ribs 9 in the channels, with complete accuracy, to locate each round at the firing position.

The reciprocation of the breech element 6 is effected by means of two pneumatic units one at the front end and the other at the rear end of said breech element. Each of these units comprises a cylindrical tube 16 which passes horizontally completely through a hole 16a through the breech element from side to side and at a level beneath the channels 7 and 8, and is rigidly secured to said breech element. Said tube 16 has its two ends open and a partition 17 at the centre divides it into two cylinders. In these cylinders stationary pistons 18 operate, said pistons being mounted on the inner ends of respective piston rods 19 whose outer ends pass through, and are mounted in, the side walls 11. Air conduits 20 extend axially through these piston rods 19 and pistons 18 and open at their inner ends into the tube 16 on each side of the partition 17, and at their outer ends which are outside the walls 11, said conduits communicate with supply pipes 21. In operation, when the breech element 6 is at the left hand end of its stroke, as for example, in Figure 2, compressed air is supplied through the left hand pipe 21 and passes through the left hand conduit 20 into the interior of the tube 16 on the left hand side of the partition 17. The tube 16, and therefore the breech element 6, are accordingly urged to the right, but, as will hereinafter appear, said breech element is retained at its left hand position until the round at the firing position in the channel 8 has been projected through the barrel 4, whereupon it is liberated and immediately flies to the right. Before it reaches the right hand end of its stroke, the left hand pipe 21 is connected to exhaust and the right hand pipe 21 is connected to the source of compressed air. This generates a thrust urging the breech element back to the left and serves to cushion the final movement of said breech element into its right hand position, which is therefore effected without shock. When said breech element reaches the right hand position it is retained there, in opposition to the thrust now urging it to the left, until the round at the firing position in the channel 7 has passed through the barrel 4, whereupon said breech element is liberated and returns to the left. Once again it is first cushioned and then retained at the left hand end of its stroke until the next round from the channel 8 has been discharged through the barrel 4 whereupon said breech element is liberated and so on.

The two said pneumatic units will of course operate in unison, and the supply of air to their supply pipes 21 is controlled by means of an air valve 22 mounted on the inner surface of the rear wall 13 of the casing as shown in Figure 13. Said valve 22 is supplied from the source of compressed air by means of a pipe 23, and a pipe 24 leads from said valve to exhaust. A pipe 25 leads to the two pipes 21 on the left hand side, and a pipe 26 leads to the two pipes 21 on the right hand side. The valve is operated by means of a lever 27, the arrangement being such that, when said lever 27 is at the left hand position illustrated, the pressure pipe 23 is connected to the pipe 25 and the exhaust pipe 24 is connected to the pipe 26, and when said lever is at the right hand position, the pressure pipe is connected to the pipe 26 and the exhaust pipe is connected to

the pipe 25. In other words, when the lever 27 is at the left hand position the breech element is urged to the right, and when said lever is at the right hand position said breech element is urged to the left.

Said lever 27 is biased by means of a fairly strong over-centre spring 28 which operates to hold it yieldingly at each of its two positions. Said lever 27 is actuated by means of two catches 29 and 30 mounted on and projecting rearwardly from the rear end of the breech element 6. These catches are spaced laterally from each other and are pivotable about pivot points 31 and 32. The arrangement is such that the left hand catch 29 is capable of yielding to the right about its pivot point in opposition to a light spring 33 but is incapable of yielding to the left. The right hand catch 30 is capable of yielding to the left about its pivot point in opposition to a light spring 34 but is incapable of yielding to the right.

In the position illustrated in Figure 13 the breech element 6 is at the left hand position and the lever 27 is at the left hand position so that said breech element is urged to the right. When the breech element is released upon firing of a round it will therefore be impelled to the right. The catch 30 will first engage the end of the lever 27 but will yield to the left and pass said lever without actuating it. A little before the breech element reaches the right hand position the catch 29 will engage the end of the lever 27 and, as said catch 29 is incapable of yielding to the left, it will move said lever 27 to the right. Thus the pipe 26 will be connected to pressure and the pipe 25 to exhaust and said breech element will be urged to the left. This will produce the aforesaid cushioning effect and said breech element will continue by inertia, to its right hand position where it will be retained. The catches 29 and 30 will now occupy the position shown in chain dotted lines. When the breech element is next released it will be impelled to the left, and in a manner converse to that when moving to the right, the catch 29 will first ride past the lever 27 after which the catch 30 will force said lever 27 to the left and will pass on to the position illustrated in full lines where the breech element is at its left hand position. At this position, the cushioning effect having been produced, the breech element is again retained and a cycle is completed and will be continued as long as the rounds continue to be fired.

Describing now the means by which the breech element 6 is retained at each end of its stroke and is liberated when each round has passed along the barrel, said breech element, about midway of its length has a hard elongated plate 35 rigidly mounted transversely on its under side and said plate 35 has notches 36 and 37 formed in its under surface an equal distance one on each side of the longitudinal centre line of said breech element. Underneath said plate 35 are mounted two catches 38 and 39. These are capable of limited up and down movement and are upwardly biased by means of respective springs 40 and 41, but said catches are fixed in respect of horizontal movements. These catches are close to, and one on each side of, the longitudinal centre line of the apparatus as a whole, and the arrangement is such that, when the breech element 6 moves into the left hand end of its stroke as shown, the catch 39 springs up into the notch 37 and restrains the breech block against movement to the right hand end of its stroke, and, when said breech block moves to the right hand

end of its stroke, the catch 38 springs up into the notch 36 and restrains the breech block against movement to the left hand end of its stroke. When a projectile from the channel 8 passes up the barrel 4 the catch 39 is pressed down for permitting the breech element to move to the right hand end of its stroke and when a projectile from the channel 7 passes up the barrel 4 the catch 38 is pressed down for permitting the breech element to move to the left hand end of its stroke, and so on.

For effecting this interlock between the discharged projectiles and the catches 38 and 39 a micro switch 42 (Figure 12) is provided at the muzzle end of the barrel 4. This micro switch has two positions, and, as will hereinafter appear, each time a projectile passes the muzzle end of the barrel, said micro switch is actuated from one of its positions to the other. When it is at one position it closes a circuit for energising a solenoid 43 and when it is at the other position it closes a circuit for energising a solenoid 44. These solenoids are coupled to an air valve 45 so that when the solenoid 44 is energised said air valve is moved to the right, and when the solenoid 43 is energised said air valve is moved to the left.

The catches 38 and 39 are mounted on a fixed elongated block 46 which extends transversely under the breech element. This block has a hole bored into each end so as to form cylinders 47 and 48. End caps 49 and 50 close these cylinders and pistons 51 and 52 move in said cylinders. Flush against the two sides of the block 46 are two unlocking plates 53. These unlocking plates are longitudinally slid able, and both of them are rigidly connected to the pistons by means of cross connecting members 54 which pass transversely through holes in the respective pistons, and at their ends, into holes in the two unlocking plates. It will thus be seen that the two pistons and the two unlocking plates are secured together to form a single unlocking unit. Transverse slots 55 are cut through the block 46 to accommodate the cross connecting members 54 when this unlocking unit is reciprocated, and it may be here pointed out these slots 55 cut into the cylinders 47 and 48 towards the inner ends of the latter which are never exposed to pressure air.

When the air valve 45 is at its left hand position illustrated, air is admitted to the right hand end of the cylinder 48 and is exhausted from the left hand end of the cylinder 47, and the unlocking unit is accordingly at its left hand position illustrated in Figure 5. At this time the breech element 6 is at its left hand position, with the catch 39 in engagement with the notch 37, and the channel 8 is accordingly in line with the barrel. When the projectile from the channel 8 passes up the barrel the micro switch 42 is actuated to de-energise solenoid 44 and energise solenoid 43. This effects movement of the air valve 45 to its right hand position, and air is accordingly exhausted from the right hand end of the cylinder 48 and is admitted to the left hand end of the cylinder 47, and the unlocking unit accordingly moves to the right. Thereupon, by a cam action between the unlocking plates 53 and the catch 39, the latter is pressed down, permitting the breech block to move to its right hand position where it is retained by the catch 38 in the notch 36. When a round is then fired from the channel 7 the micro switch 42 re-energises the solenoid 44 and the air valve 45 returns to the left hand position and the unlocking unit returns to

its left hand position, and a cam action between its unlocking plates 53 and the catch 38 presses the latter down and permits the breech element to return to the left hand position. One cycle has now been completed and the cycles will continue as long as the rounds are fired.

Describing now the cam action between the unlocking plates 53 and the catches 38 and 39, it will be seen that each of these catches consists of the upturned end of rectangular and fairly massive plates 56. These plates 56 are of substantially the same width as the block 46, and each one is mounted in a slot 57 cut across the upper surface of the block 46 with the ends of said plates abutting against the sides of said slots and the sides of said plates substantially flush with the sides of said block. The ends of said plates which carry said catches 38 and 39 are towards each other so that said catches are close together as before stated. The other ends of said plates are convexly rounded and engage in concavely rounded recesses in the sides of the slots so that pivotal mounting is constituted enabling the catches 38 and 39 to be raised and lowered as stated. It will be seen that the thrust of the breech element 6, when this is being retained by one of the catches, is taken by the abutment of the end of the respective plate 56 against the side of its slot 57.

Each of the plates 56, at its end which carries the catch 38 or 39, has two integral cam pieces 58 projecting laterally therefrom. And the two cam pieces 58 on each side move in a cam slot 59 in the adjacent surface of the respective unlocking plate 53. It will readily be seen from the drawing that the upper surface of each cam slot 59 so co-operates with the upper surfaces of the two cam pieces 58 that, when the cam plates 53 move to the left the catch 38 is depressed and the catch 39 is permitted to rise, and that when the cam plates move to the right the catch 39 is depressed and the catch 38 permitted to rise. It will also be observed that, as the cam plates complete their movement to one or other position, the lower surface of each cam slot 59 moves underneath the lower surface of that cam piece 58 which has just risen under the influence of the spring 40 or 41, so that the respective catch 38 or 39 is held positively at the up position.

Describing now the operation of the micro switch 42 by the rounds passing up the barrel 4, said micro switch is actuated by means of a plunger 60 and is of the well-known kind which controls two circuits and changes over from one to the other according to whether said plunger is depressed or released. In the present instance the two circuits are of course the circuits of the two solenoids 43 and 44.

Said plunger 60 is controlled by means of a cam 61 which is in the form of a disc with its periphery cut away in four places to form four flats 62 spaced at right angles to each other about the axis of the disc. This cam is mounted fast on a rotatable shaft 63 with its periphery in engagement with the plunger 60, and the arrangement is such that said plunger is at the released or depressed position according to whether it is in engagement with a flat of said cam or with a hump between flats. Said shaft 63 is mounted in a slot 64 formed through the wall of the barrel 4 said shaft being transverse to the direction of movement of the projectiles which is indicated by the arrow X. A ratchet wheel 65 is also mounted fast on said shaft, and a shoe 66 is mounted so as to be loosely rotatable

on said shaft, and said shoe is biased about said shaft by means of a spring 67 to a limiting position at which a projection 68 thereon abuts against a shoulder 69 on the inside of said slot 64. At this limiting position said shoe 66 projects into the bore of the barrel 4 so as to be engaged by the passing rounds. Said shoe 66 carries a pawl 70 which is biased by means of a spring 71 into engagement with the ratchet wheel.

As will be clear from the drawing, each time a round passes, the forward end of said round will engage the shoe 66 and press it in opposition to its spring 67, out of the bore of the barrel. Thus said shoe rotates about the shaft 63 in a clockwise direction to the position indicated in chain-dotted lines. In this direction the pawl 70 can ride freely over the teeth of the ratchet wheel 65. Actually there are eight teeth on said ratchet wheel and said pawl rides over one tooth. The shoe 66 remains at the chain-dotted line position until the rear end of the projectile has passed it, that is until said projectile is almost clear of the barrel. After this said shoe returns, under the influence of its spring 67 to the full line position, and the pawl 70 now engages a ratchet tooth in the operative direction and turns the ratchet wheel, and therefore the shaft 63 and the cam 61, through half a right angle. Thus if a flat of the cam was previously presented to the plunger 60 a hump will now be presented to it, so that the switch 42 will have changed over. Obviously after the next round has passed a flat will again be presented to the plunger and the switch will again be changed over, and so on.

It will be observed that the change-over of said switch 42 does not take place until after each round has substantially left the barrel, so the new round cannot be ever moved into the firing position until the preceding round has left the barrel.

It will be seen that the switch 42 is mounted on the barrel by means of a bracket 72, and the whole mechanism is shielded by means of a suitable cover 73 detachably mounted on the barrel. The reference 74 designates a cable cover which encloses the circuit conductors.

In construction it will be seen that the portion of the shoe 66 which is mounted on the shaft 63 is bifurcated and that the ratchet wheel 65 is accommodated between the two lugs so formed.

Describing now the operation of the air valve 45, this is a longitudinally movable piston valve. It is coaxial with, and between, the plungers of the two solenoids 43 and 44. At its right hand end it is connected by a link 75 to the plunger of the solenoid 44 and at its left hand end it is connected by a link 76 to the plunger of the solenoid 43. Said valve slides in the bore of a block 77, which is flush against the side of a block 78 which forms the support for the aforesaid block 46 in which the cylinders 47 and 48 are formed.

The air supply is introduced through a conduit 79 in the block 77 which conduit 79 runs first vertically upwards then horizontally to the left parallel to the valve 45 and then horizontally and towards said valve 45 where it joins the bore of said valve where indicated in chain dotted lines in Figure 8.

The exhaust takes place through a conduit 80 which runs horizontally into said block 77 parallel to the valve 45, and which joins the bore of said valve by way of two short radial conduits 81. The connection from the bore of the valve

to the right hand cylinder 48 is by way of a conduit 82 in the block 77 and a connecting conduit 83 in the block 78. The conduit 83 leads to a port 84 in a plate 85 underlying the block 46, which port leads to a groove 86 in the upper surface of said plate 85 and forming, together with said block 46, a conduit. Said groove 86 leads to a port 87 in the block 46 which leads into the right hand end of the cylinder 48.

The connection from the bore of the valve 45 to the left hand cylinder 47 is by way of a conduit 88 in the block 77 and a connecting conduit 89 in the block 78. The conduit 89 leads to a port 90 in the plate 85 which port leads to a groove 91 in the upper surface of said plate, and forming, like the groove 86, a conduit, said groove 91 leads to a port 92 in the block 46 which leads into the left-hand end of the cylinder 47. The valve 45 has two reduced portions 93 and 94, and it will be seen that, when said valve is at the left-hand position shown, the space surrounding the reduced portion 94 connects the air-supply conduit 79 with the conduit 82 and therefore with the cylinder 48, while the space surrounding the reduced portion 93 connects the left hand exhaust conduit 81 with the conduit 88 and therefore with the cylinder 47. At this position of the valve 45 the right hand exhaust conduit 81 is closed by said valve.

In corresponding manner, when the valve 45 is at its right-hand position, the space surrounding the reduced portion 93 will connect the air-supply conduit 79 with the conduit 88 and therefore with the cylinder 47, while the space surrounding the reduced portion 94 connects the right hand exhaust conduit 81 with the conduit 82 and therefore with the cylinder 48. At this position the left hand exhaust conduit 81 is closed by the valve.

A spring loaded over-centre device is provided for ensuring that the valve 45 will move with a snap action fully into each of its two positions. This device comprises a short rod 95 pivotally mounted in a slot 96 in the fixed block 77 so as to turn about the axis 97. A second short rod 98 engages telescopically in an axial bore hole formed in one end of said rod 95. A spring 99 urges said rods to the extended position relative to each other, and the outer end of the rod 98 is rounded and mates in a corresponding rounded recess in the periphery of the valve 45. The operation of said device is deemed obvious.

Describing now the mechanism by which the column of rounds 3 in the chute (1 or 2) which is in registration with the channel (7 or 8) is enabled to move down a step to feed the leading round into the channel, a horizontal rotatable shaft 100 parallel to the rounds is mounted just outside and close alongside each chute. This shaft has mounted on it a number of escapement elements 101, each of which is in the form, as best shown in Figure 2, of a disc with three arcuate "bites," spaced at one hundred and twenty degrees to each other, cut out of its edge so as to form a three pronged star. These escapement elements project through slots 102 in the adjacent wall of the chute.

Each shaft 100 at its rear end (i. e. at a position which is cut away in Figure 1) has rigidly mounted on it a ratchet wheel 103 with three ratchet teeth. The shafts are biased by means of springs 104 to rotate in the direction indicated by the arrows, and normally each shaft is held against rotation by means of a pawl 104 engaging with the ratchet wheel. The position of each

shaft when restrained by said pawl and ratchet wheel is such that one of the prongs of each of the escapement elements 101 projects into the adjacent chute so as to come under and obstruct the lowermost round, with said round filling into the arcuate "bite" above said prong as best shown in Figure 2. Thus both columns of rounds are prevented from moving downwardly.

Shortly after the breech element 6 commences to move from one position to the other (say from the left hand position to the right hand position) an unlocking arm 105 associated with said breech element actuates the right hand pawl 104 to cause the same momentarily to release its ratchet wheel 103. The right hand shaft 100 together with its escapement elements 101 is therefore free to rotate under its bias in the direction to permit the lowermost round in the chute 2 to move down. By this time the leading portion of the breech element will be underneath said lowermost round and will support it until the channel 8 comes immediately beneath it, whereupon said lowermost round will fall into said channel 8. During this movement, as will be clear from Figure 2, the shaft 100 with its escapement elements 101 will rotate until the next ratchet tooth is stopped by the pawl 104, and the next prong of each of the escapement elements will now come under, and will obstruct, the next round, now the lowermost one in the chute.

On the return movement of the breech element the aforesaid unlocking arm 105 is adapted to ride past the said right-hand pawl 104 without actuating it, but a like left hand unlocking arm 105 now actuates the left-hand pawl 104, and thus the lowermost round of the left-hand chute 1 is released to fall into the left-hand channel 7. The cycle may now continue indefinitely.

Describing now more particularly the pawls 104 and their unlocking arms 105, immediately above a flange-like projection 106 at the back end of the breech element 6 a transverse slot is cut in the roof 10 of the casing, and, in this slot is fixed an inverted channel-shaped piece 107. The roof and part of the side walls of this inverted channel-shaped piece is cut away at two places to accommodate the pawls 104. It is deemed that the manner in which these pawls are pivotally mounted in these cut away spaces is clear from Figure 2. Each of said pawls is upwardly biased into engagement with its respective ratchet wheel 103 by means of a spring loaded plunger 108 in the thickness of one or each of the side walls of the channel-shaped piece 107.

Each of said pawls has downwardly depending from its underside two parallel longitudinal webs 109, and each of these webs, at its lower edge, has an inwardly turned flange 110 forming an inclined cam surface.

Pivotally mounted in slots 111 in the flange portion 106 of the breech element 6, so as to pivot about pins 112 traversing said slots, are the two unlocking arms 105. Each of these is in the form of a relatively thin plate or web which is capable of passing between the flanges 110 of the respective pawl, an inclined cross flange 113 being formed at the upper edge of the web at the end remote from the pivot pin 112. Each of these unlocking arms 105 is biased upwardly about its pivot pin 112, by means of a spring which has been omitted for the sake of clearness, to a limiting position determined by the engagement of a stop on said unlocking arm with a stop on the inside of the slot 111 (indicated in dotted lines in Figure 2).

The operation will now be clear, when the breech element 6 moves to the right from the left hand position shown in Figure 2, after a short distance has been passed the web of the right hand unlocking arm 105 will pass between the flanges 110 of the right hand pawl 104, and the under surface of the inclined cross flange 113 of said right-hand unlocking arm will engage the over surfaces of said flanges 110 of the right hand pawl 104 and will press said pawl down in opposition to its spring bias thereby liberating the ratchet wheel 103. This pressing down of said pawl is only momentary, because immediately the flange 113 passes the flanges 110, said pawl will spring up again, and it does this in good time to arrest the next tooth of the ratchet wheel 103, more particularly because the rotation of said ratchet wheel is delayed by the delay in the down passage of the lowermost round caused by its need to wait for the channel 8.

At about the same time as the right hand pawl 104 is thus actuated by the right hand unlocking arm 105, the upper surface of the cross flange 113 of the left-hand unlocking arm 105 will engage the under surface of the flanges 110 of the left hand pawl 104. This will simply press said unlocking arm 105 slightly downwards in opposition to its spring bias and permit it to ride past said pawl 104 without moving it. Obviously when the breech element makes its return movement to the left-hand position the left-hand unlocking arm 105 will release the left-hand pawl 104, and the right hand unlocking arm 105 will ride past the right-hand pawl.

With regard to the pushers 5 which bias the rounds down their respective chutes 1 and 2, the manner in which these pushers are operated forms no part of the present invention, and they may be operated in any suitable way. In the arrangement illustrated they are operated in a manner which is substantially identical with that described with reference to Figures 7 and 8 of prior specification No. 592,714. Thus the pusher elements 5 of each chute (equivalent to the elements 32 of said prior specification) are mounted on endless chains which run over sprockets within channel-shaped housings 114 (equivalent to those 45 of said prior specification). The upper sprockets are fast on a shaft 115 (equivalent to the shaft 36 of said prior specification). Said shaft 115 is driven by an electric torque motor 116 mounted on the wall of the respective chute, which motor, through a suitable gear train drives a pinion 117 which is loose on said shaft and is connected to the shaft by means of a coil spring 118, the said parts 116, 117 and 118 being equivalent to the parts 53, 55 and 56 of said prior specification. Further details are as described in said prior specification.

It will be seen that the housings 114 constitute the means for carrying the bearings for the shaft 100. This shaft may pass through said housings either just above or just below the lowermost sprockets (35 in said prior specification). The aforesaid springs 119, which bias said shafts 100, are adapted to be manually primed in any suitable way, and, after each priming they are capable of effecting the total rotation of the shaft required for a full charge of rounds in the respective chute.

Reverting to Figure 4 the references 120 and 121 designate two micro switches each of which has two positions which will be termed *a* and *b*. When the unlocking unit comprising the unlocking plates 53 moves to the left-hand position it

operates switch 120 to position *b* and when it moves out of the left-hand position said switch 120 returns to position *a*. In like manner when said unlocking unit moves to the right-hand position it operates switch 121 to position *b* and when it moves out of said right-hand position said switch 121 returns to position *a*. Said two switches 120 and 121 are connected in series in the firing circuit, in such a way that said circuit is positively broken when both switches are at position *a*, but can be established by the normal firing means when either of said switches is at position *a* and the other is at position *b*. Thus it is ensured that from the moment said unlocking unit leaves one of its two positions and until it fully reaches the other the firing mechanism cannot be established. This is simply a precaution and said switches can, if desired, be dispensed with.

More particularly each of said switches is normally at the position *a* and is actuated to position *b* when a thrust rod 122 is pressed against its plunger. When the unlocking unit moves into its left-hand position the thrust rod 122 of the switch 120 is actuated by the left hand end of one of the unlocking plates 53, and said switch is actuated to its position *b*. Immediately said unlocking unit leaves its left-hand position, said thrust rod is disengaged by said unlocking plate 53 and the switch returns to position *a*. The switch 121 is operated in like manner by the other end of the plate 53 engaging the other thrust rod when the unlocking unit moves into and leaves its right hand position.

The firing system itself forms no part of the present invention and any suitable firing system can be employed. The invention clearly lends itself to both single fire control and automatic fire.

It will be seen that the micro switches 120 and 121 are mounted on recesses in end blocks 123 and 124 at the ends of the block 78.

It will be appreciated that, when a round is fired there is a large force, caused by the blast pressure, tending to force the breech element 6 away from the under surface of the roof 10 of the main casing. Actually the blast pressure may be about sixty pounds per square inch which means that the separating force may be about ten tons. To withstand this force it is necessary to lock the breech element 6 to the under surface of the roof 10, and, in the present arrangement this is effected by providing lateral slots 125 of dove-tail section in the said under surface and co-engaging tongues 126 of the same section on the upper surface of the breech element. These tongues and slots are in permanent engagement and form guide means for the breech element in making its to-and-fro movement.

All other structural features are deemed clear from the drawing.

I claim:

1. An apparatus for discharging rounds of ammunition, comprising two containers for the rounds, a reciprocable breech element, said breech element including two receptacles, one of said receptacles being adapted to receive a round from one of said containers when said breech element is at one end of its stroke, while the other receptacle holds a round previously received from the other container, at a common location to enable the round to be discharged, and said other receptacle being adapted to receive a round from said other container when said breech element is at the other end of its stroke, while the first-named receptacle holds a round

previously received from the first-named container, at said common location.

2. An apparatus for discharging rounds of ammunition, comprising a barrel, two containers for the rounds, each container being formed with an elongated outlet through which a round can pass at right angles to its axis, a breech element adapted to reciprocate in a direction transversely to the barrel, said breech element being formed with two channels transverse to the direction of movement of said breech element, one of said channels registering with the outlet of one of said containers when said breech element is at one end of its stroke and thereby receiving a round from said container, while the other channel holds a round, previously received from the other container, at a common location accurately in line behind said barrel to enable said round to be discharged through said barrel, and the other channel registering with the outlet of said other container when said breech element is at the other end of its stroke and thereby receiving a round from said container, and the first-named channel holding a round, previously received from the first-named container at said common location to enable said round to be discharged through said barrel.

3. An apparatus for discharging rounds of ammunition, comprising two containers for the rounds, a breech element adapted to reciprocate, said breech element including two receptacles, and means operable, when said breech element is at one end of its stroke, that one of said receptacles receives a round from one of said containers, and the other receptacle holds a round, previously received from the other container, at a common location, and, when said breech element is at the other end of its stroke, the last-named receptacle receives a round from the last-named container and the first-named receptacle holds a round, previously received from the first-named container, at said common location, means for discharging each round at said common location, means for positively retaining said breech element at each end of its stroke until the round at said common location is discharged, and means responsive to said last-named round being discharged for moving said breech element to the other end of its stroke.

4. An apparatus for discharging rounds of ammunition, comprising a barrel, two containers for the rounds, each container being formed with an elongated outlet through which a round can pass at right angles to its axis, a breech element adapted to reciprocate in a direction transversely to the barrel, said breech element being formed with two channels transverse to the direction of movement of said breech element, means operable, when said breech element is at one end of its stroke, that one of said channels registers with the outlet of one of said containers and thereby receives a round from said container, and the other channel holds a round, previously received from the other container, at a common location accurately in line behind said barrel, and, when said element is at the other end of its stroke, the last-named channel registers with the outlet of the last-named container and thereby receives a round from said container, and the first-named channel holds a round, previously received from the first-named container at said common location, means for discharging each round at said common location, whereby it passes along the bore of said barrel, an element

normally projecting into said bore, and adapted to be actuated by the passage of a round along said bore, means for positively retaining said breech element at each end of its stroke until said element is so actuated, and means responsive to said element being so actuated for moving said breech element to the other end of its stroke.

5. An apparatus for discharging rounds of ammunition, comprising a barrel, two containers for the rounds, each container being formed with an elongated outlet through which a round can pass at right angles to its axis, a breech element adapted to reciprocate in a direction transversely to the barrel, said breech element being formed with two channels transverse to the direction of movement of said breech element, means operable, when said breech element is at one end of its stroke, that one of said channels registers with the outlet of one of said containers and thereby receives a round from said container, and the other channel holds a round, previously received from the other container, at a common location accurately in line behind said barrel, and, when said element is at the other end of its stroke, the last-named channel registers with the outlet of the last-named container and thereby receives a round from said container, and the first-named channel holds a round, previously received from the first-named container at said common location, means for discharging each round at said common location, whereby it passes along the bore of said barrel, an element normally projecting into said bore near the muzzle end thereof and adapted to be moved from its normal position by engagement by a round passing along said bore and to return to said normal position when said round has passed, means for positively retaining said breech element at each end of its stroke until said element has moved from and returned to said normal position, and means responsive to said element moving from and returning to said normal position, for moving said breech element to the other end of its stroke.

6. An apparatus for discharging rounds of ammunition, comprising two containers for the rounds, a breech element adapted to reciprocate, said breech element including two receptacles, and means operable, when said breech element is at one end of its stroke, that one of said receptacles receives a round from one of said containers, and the other receptacle holds a round, previously received from the other container, at a common location, and, when said breech element is at the other end of its stroke, the last-named receptacle receives a round from the last-named container and the first-named receptacle holds a round, previously received from the first-named container, at said common location, means for discharging each round at said common location, a motor device operable, upon said breech element reaching each end of its stroke, to return it to the other end of its stroke, latching means for latching said breech element positively at each end of its stroke, and means operable, in response to each round being discharged, for actuating said latching means to the unlatching state.

7. An apparatus for discharging rounds of ammunition, comprising two containers for the rounds, a breech element adapted to reciprocate, said breech element including two receptacles, and means operable, when said breech element is

at one end of its stroke, that one of said receptacles receives a round from one of said containers, and the other receptacle holds a round, previously received from the other container, at a common location, and, when said breech element is at the other end of its stroke, the last-named receptacle receives a round from the last-named container and the first-named receptacle holds a round, previously received from the first-named container, at said common location, means for discharging each round at said common location, a fluid pressure motor device operable, upon said breech element reaching each end of its stroke, to return it to the other end of its stroke, latching means for latching said breech element positively at each end of its stroke, a reciprocable unit adapted, on movement to one end of its stroke, to unlatch said breech element when at one end of its stroke, and, on movement to the other end of its stroke, to unlatch said breech element when at the other end of its stroke, fluid pressure means for moving said reciprocable unit from each end of its stroke to the other, a two-position fluid control valve for controlling said fluid pressure means to move said reciprocable unit in its two directions, and electrical means responsive to each round moving along its discharge path to actuate said valve from either of its two positions to the other.

30 8. An apparatus for discharging rounds of ammunition, comprising a barrel, two containers for the rounds, each container being formed with an elongated outlet through which a round can pass at right angles to its axis, a breech element adapted to reciprocate in a direction transversely to the barrel, said breech element being formed with two channels transverse to the direction of movement of said breech element, means biasing the rounds of each container to the outlet of said container, escapement mechanism associated with each container, means operable, just before said breech element reaches one end of its stroke, that one of said escapement mechanisms operates to permit one round to pass through the outlet of the container corresponding to said escapement mechanism, and when said breech element reaches the last-named end of its stroke one of said channels registers with the last-named outlet and thereby receives the last-named round, and, at the same time the other channel holds a round previously received from the other container, at a common location accurately in line behind said barrel, to enable said round to be discharged through said barrel, and means operable, just before said breech element reaches the other end of its stroke, that the other escapement mechanism operates to permit one round to pass through the outlet of the other container, and when said breech element reaches said other end of its stroke, the other channel registers with said outlet end of said other container and thereby receives the last-named round, and at the same time, the first-named channel holds a round previously received from the first-named container at said common location.

9. An apparatus for discharging rounds of ammunition, comprising a barrel, a plurality of containers for the rounds, a reciprocable breech element, means responsive to each reciprocating movement of said breech element in one direction for conveying a round from one container, and, responsive to each reciprocating movement in the other direction for conveying a round from another container, alternately to a common

location accurately in line behind said barrel, means for discharging each round at said common location through said barrel, an element normally projecting into said barrel in the path of and actuatable by each round discharged, means for positively retaining said breech element at each end of its stroke until said element is so actuated, and means responsive to said element being so actuated for moving said breech element to the other end of its stroke.

10. An apparatus for discharging rounds of ammunition, comprising a plurality of containers for the rounds, a reciprocable breech element, means responsive to each reciprocating movement of said breech element in one direction for conveying a round from one container, and, responsive to each reciprocating movement in the other direction for conveying a round from another container, alternately to a common location, means for discharging each round at said common location, a motor device operable upon said breech element reaching each end of its

stroke to urge it towards the other end of its stroke, latching means for latching said breech element positively at each end of its stroke, and means operable in response to each round being discharged, for actuating said latching means to the unlatching state.
